Primary Examiner — Lauren R Calve(74) *Attorney, Agent, or Firm* — IPUSA, PLLC(57) **CLAIM**

The ornamental design for a packaging container, as shown and described.

DESCRIPTION

FIG. 1 is a perspective view of a packaging container, showing my new design;

FIG. 2 is a front view thereof;

FIG. 3 is a rear view thereof;

FIG. 4 is a top plan view thereof;

FIG. 5 is a bottom plan view thereof; and,

FIG. 6 is a right side view thereof, the left side view being a mirror image.

The broken lines shown in the drawings represent portions of the packaging container that form no part of the claimed design. The shading on the figures indicates transparency.
